UNITED STATES PATENT OFFICE.

EDWARD S. DE TAMBLE, OF RACINE, WISCONSIN, ASSIGNOR TO RACINE ACCESSORIES
MANUFACTURING CO., OF RACINE, WISCONSIN, A CORPORATION OF WISCONSIN.

DESIGN FOR A WHISTLE.

59,340.

Specification for Design.

Patented Oct. 11, 1921.

Application filed January 20, 1921. Serial No. 438,759. Term of patent 7 years.

To all whom it may concern:

Be it known that I, EDWARD S. DE TAMBLE, a citizen of the United States, residing at Racine, in the county of Racine and State of Wisconsin, have invented a new, original, and ornamental Design for Whistles, of which the following is a specification, reference being had to the accompanying drawing, forming part thereof.

Figure 1 is a perspective view of a whistle showing my new design; and

Fig. 2 is a cross sectional view thereof looking toward its upper end.

I claim:

The ornamental design for a whistle, as shown.

EDWARD S. DE TAMBLE.
